ORE CLASSIFIER

William Eugene Endrezze, Butte, Mont.

Application July 8, 1927, Serial No. 204,260

11 Claims. (Cl. 209—462)

The present invention relates to ore classifiers and has for its prime object to provide improvements in apparatus for separating and classifying materials which have different settling rates in liquid, whether such difference is caused by a variation in the specific gravity of the particles, as in the concentration of ores, or in the size of the particles when homogeneous, as in the separation of sands, and slimes.

10 The apparatus disclosed herein is especially designed for classifying the sands and slimes in wet crushed pulp for cyaniding, and for convenience it will be assumed in the following description that the pulp is being treated for that purpose.

15 According to the present invention the wet pulp from a suitable crusher or pulverizer is continuously conveyed to a settling trough, where the sands settle to the bottom by gravity, while the slimes remain in suspension in the liquid. The 20 slimes flow over into launders which conveys them away to a suitable receptacle removed from the classifier, while the sands are moved upwardly along the inclined bottom of the trough and delivered to another launder, which conveys them 25 away for further crushing and grinding. For the purpose of moving the sands out of the trough, rakes or scrapers are reciprocated back and forth over the bottom of the trough in such a manner as to move the sands toward the upper end of 30 the trough on the outstroke, but which are elevated above the plane of the sand on their instroke. This raking operation is effective not only in moving the sand as fast as it settles upon the bottom of the trough, but it also serves to 35 loosen or agitate the sand by first forming it into small piles and then allowing it to settle, while at the same time progressively moving it upward and outward along the inclined bottom of the trough. The rake, while effectively removing the 40 sands, do not so agitate the liquid in the upper stratum of the bath as to interfere with the settling of the sands. The operation results in keeping the slimes in suspension and allowing the sands to settle out.

45 While the greatest portion of the slimes are separated from the sands in this way, there are still some present in the settled sands which must be removed. To accomplish this, I provide means for washing the settled sands after they emerge 50 from the settling bath and just before their delivery to the launder which conveys them away. An important object of the invention lies in an improved structure for accomplishing this purpose which includes a plurality of alternately arranged water and air cells located near the

sand delivery end of the trough through which air and clear liquid is forced upwardly through the sand as it passes over them, resulting in the elimination of the remaining slimes, which are carried back with the incoming liquid to the settling bath, very little of such clear liquid being allowed to pass out with the sand. 5

I preferably divide the settling trough into two parts, using two sets of rakes operating alternately in opposite directions whereby the weight of 10 the moving parts is counter balanced, and the overflow of the liquid into the slime receiving trough is made more uniform and even.

One of the most important objects of the improved structure disclosed herein is to provide 15 inwardly and upwardly inclined back and side walls for the trough for the prevention of the formation of mud banks.

Another object of the present invention is to place the side launders in a convenient and an 20 effective position upon the classifier trough for the receiving of the slimes and fines discharged from the trough.

Other objects of the invention are to provide an apparatus of this nature which is simple in 25 its construction, thoroughly efficient and reliable in its operation of separating the sands and slimes and otherwise well adapted to the purpose for which it is designed.

With the above and numerous other objects in 30 view as will appear as the description proceeds, the invention resides in certain novel features of construction, and in the combination and arrangement of parts as will be hereinafter more fully described and claimed. 35

In the drawings:

Figure 1 is a sectional side elevation of the apparatus embodying the features of my invention,

Figure 2 is a top plan view thereof,

Figure 3 is a vertical transverse section taken 40 substantially on the line 3—3 of Figure 1,

Figure 4 is a side elevation of the apparatus,

Figure 5 is a fragmentary plan view of the bottom of the trough showing the perforated or screen covering for the air and water cells, 45

Figure 6 is a sectional view through one of the cells, and

Figure 7 is a perspective view of one of the rake plates.

The wet pulp is conveyed by a feed-laund 5 to 50 a settling trough indicated at 6 in Figure 1. A spout structure 7 leads from opening 8 in the feed-laund 5 to the settling trough 6 and has a cross member 9 mounted therein with a valve plate 10 slidable on the member across the outlet end of 55

the spout structure 7 to spread the feed in a thin layer or stream and cause the flow to be continuous from the feed spreader box. The settling trough 8 is inclined as shown in the drawings, the liquid level being indicated by the line 11. Suitable supports 12, 13 and 14 are employed to hold the trough at the desired inclination. Preferably the feed launder 5 is located about midway between the center and the lower end of the trough. A launder 15 for carrying away the slimes has side branches 15' and is located at the lower end of the trough, extending laterally across said trough at the lower end and longitudinally along the sides thereof for a distance slightly behind the feed launder 5. The bottoms of the portions 15' are inclined toward the main portion 15 which has an outlet pipe 16 depending therefrom. A launder 17 for carrying off the sands is located at the upper end of the trough. Preferably the trough is divided into two parts by a partition 18 which is high enough merely to prevent sands from spreading from one part or division of the trough to the other. In each division of the trough is located a rake or scraper indicated generally by the letters R. Each rake R comprises longitudinal bars 19 and a series of transverse plates 20 attached to the bars in any suitable way. The rake bars are supported by hangers 22 and 23, standards 25 rise from the sides of the trough between the mid portion thereof and the upper end thereof and support blocks 26 in which is mounted a shaft 27 having a pair of bellcranks 28 rockable thereon, one for each of the divisions of the trough. Links 29 are pivotally engaged as at 30 with the upper ends on the shorter arms on the bellcranks levers 28 and have lateral cams 31 engaged by the hooked upper ends of hangers 23. A gear casing 32 is mounted on the partition 18 and has mounted therein a drive gear 33 meshing with a relatively large gear 34 fixed to a shaft 35 journaled in the casing and extending beyond the sides thereof. A pair of cams 36 are mounted on the shafts 35 and have pivotally engaged therewith as at 37 pitman rods 38 which are pivotally engaged with hangers 22 as at 39. The longer arms of the bellcranks 28 which depend downwardly from the shaft 27 have journaled intermediate their ends rollers 40 which are engaged by cams 36 for rocking the bellcranks 28 and lifting upwardly through links 29 on the hangers 23. Rods 41 are pivotally engaged with the lower extremities of the bellcranks 28 as at 42 and are pivotally engaged with cranks 43. A shaft 45 is journaled in standards 46 on the sides of the trough and the cranks 43 are attached thereto and depend downwardly therefrom. Cranks 47 are attached to the shaft 45 and are pivotally engaged as at 48 with members 49 on a rail 49' supported by standards 46. Cranks 50 project from the shafts 45 and are pivotally engaged with links 51. These links 51 are pivotally engaged on hangers 22. It will thus be seen by referring to Figure 1 that to one side of the rake mechanism that as the gear 33 driven in any suitable manner as is indicated at 33' in Figure 2, rotates in a clockwise direction the gear 34 is driven in a counter-clockwise direction and the rake is moved upwardly from the incline of the trough until the cam 36 actuates the bellcrank 28 through the roller 40 to swing said bellcrank in a counter-clockwise direction causing the rear end of the rake to be lifted through link 29 and hanger 23 and to cause the forward end of the rake to be lifted through link 41, crank 43, crank 50 and 51 and at the same time the rod 38 moves the rake

forwardly, that is, toward the lower end of the incline of the trough.

It will be apparent from an inspection of Figure 2 that the rakes operate alternately, that is, while one is moving up the incline, the other is moving downwardly of the incline.

The rakes in the two compartments or divisions of the trough are similar in all respects and because of their alternate operation they counter-balance the weight of the moving parts and serve to make the overflow in the launder 17 more steady and uniform.

Particular attention is now directed to Figures 1 and 3 wherein it will be seen that the lower wall 66 and the adjacent portions of the side walls as 15 at 61 are inclined inwardly of the trough and upwardly. These inclined end and side wall portions prevent the formation of mud banks in such a way as to make all particles of the feed that do not flow out of the trough by way of overflow, 20 to settle to the bottom directly in the path of the rakes or scrapers and here the rakes or scrapers are continuously carrying these particles upwardly along the bottom of the trough and out of the bath to be dumped into the suitable sand launder 25 17 at the upper end of the classifier. Thus by the inclining of the lower end wall and the adjacent side wall there is no dead space for these particles to rest upon that would serve as a foundation to build a mud bank upon the particles that 30 are held in suspension at the lower end of the trough have no chance to form overhanging mud-banks by sticking to the lower end wall and the adjacent side wall as the angle produced by an overhanging mudbank is taken up in the slant 25 of these wall sections and therefore any tendency to form an overhanging mud bank is done away with in this manner.

For the purpose of cleaning the settled sands after their emergence from the liquid and just before their delivery to the launder 17, I provide a series of cells 62 and 63 alternately arranged as is clearly indicated in Figure 1. The cells 62 are air cells and have pipes 64 leading thereto and the cells 63 are water cells and have supply pipes 65 leading thereto. These cells are open at their tops registering with an opening 67 in the bottom of the trough or tank structure and are covered by foraminous sheet material 68 such as screen wire, canvas, or the like. A clear cyanide 50 solution may be used in place of the water. The liquid and air are forced upwardly through the sands and said sands will be elevated slightly and agitated, while the contained slimes are separated and flow back into the bath.

It will be observed that the settled sand is in motion only half the time, but is exposed to the action of the upward flow of liquid and air from the cells 62 and 63 both while in motion and also while at rest, thus giving the liquid and air ample opportunity to keep the settled sand loose and open to allow the escape of the slime. This action of the upward current through the settled sands has been found to be very efficient in the separation of the slimes from the sand. The inward movement of the rakes causes an agitation of the particles in suspension in the lower stratum of the bath and thus tends to free the settled particles of sand from the adhering slime and keep the latter in suspension. In this manner perfectly clean leachable sands are obtained, while the slimes are entirely free from sand.

From the above detailed description it will be seen that this improved classifier is compact, requiring but little space and necessitating little

attendance, no matter how much the ore may vary in its nature and both clean sand and clean slimes are made in one operation. The sand is delivered particularly free from liquid. In the foregoing description I have referred to the rapidly settling particles as "sands" and to the slowly settling particles as "slimes", but it will be understood by those skilled in this art that the apparatus may be employed to classify materials not ordinarily thus designated and I wish it understood that both in the specification and in the claims I do not wish to be confined to an apparatus for separating sands and slimes.

It is thought that the construction, operation and advantages of this invention will now be clearly understood by those skilled in this art without a more detailed description thereof. The present embodiment of the apparatus has been disclosed in detail merely by way of example since in actual practice it attains the features of advantage enumerated as desirable in the statement of the invention and the above description. It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:—

1. An apparatus for separating and classifying materials of different settling rates, comprising a stationary inclined settling trough with a lower end wall and adjacent side walls the lower end wall being inclined at an acute angle to the bottom of the trough in front of the vertical and the adjacent portions of the side walls being inclined upwardly and inwardly to prevent the formation of mud banks on either of said walls, and means for conveying the settled material toward the upper end of the trough, said conveying means having a portion thereof positioned with the walls disposed in overhanging relation with respect thereto.

2. An apparatus for separating and classifying material of different settling rates comprising an inclined stationary settling trough with a lower end wall and side walls, the lower end wall being inclined at an acute angle to the bottom of the trough in front of the vertical and the adjacent portions of the side walls being inclined upwardly and inwardly to prevent the formation of mud banks; means below the liquid level of the bath for conveying the settled material toward the upper end of the trough and disposed partially with the walls in overhanging relation with respect thereto, and means for operating said conveyor.

3. As a new article of manufacture, a stationary inclined settling trough for an apparatus for classifying crushed ores having an inclined bottom, side and end walls rising therefrom, the lower end wall being inclined at an acute angle to the bottom of the trough in front of the vertical.

4. As a new article of manufacture, an inclined stationary settling trough for an apparatus for classifying crushed ores having an inclined bottom, and lower end and side walls rising therefrom, the lower end wall being inclined at an acute angle to the bottom of the trough in front of the vertical and the adjacent portions of the side walls being inclined upwardly and inwardly of the trough, for the prevention of the formation of the mud banks.

5. An apparatus for settling and classifying material of different settling rates comprising an

inclined stationary settling trough, the lower end wall being inclined upwardly and inwardly at an acute angle to the bottom of the trough in front of the vertical and the adjacent portion of the side walls being inclined upwardly and inwardly to prevent the formation of mud banks, means below the liquid level of the bath for conveying the settled material step by step toward the upper end of the trough and disposed partially with the wall in overhanging relation with respect thereto, and means for operating said conveyor.

6. An apparatus for classifying crushed ores comprising a settling trough having a conveyor operating therein to remove the settled sand therefrom, said settling trough when set in position for operation having means for the prevention of mud banks at the lower end wall thereof, said lower end wall inclining inwardly and upwardly at an acute angle to the bottom of the trough in front of the vertical and with respect to the conveying means and said end wall further having its upper edge constituting a weir over which the slime from the trough may flow.

7. An apparatus for classifying crushed ores comprising a settling trough having a conveyor operating therein for removing the settled sand therefrom, said settling trough having means including a lower end wall and side walls for the prevention of mud banks the lower end wall being inclined at an acute angle to the bottom of the trough in front of the vertical, and the side walls inclining inwardly and upwardly and with respect to the conveying means and said side walls further being exposed in overhanging relation with respect to said conveying means and having their upper edges constituting weirs over which slimes from the trough are adapted to flow.

8. An apparatus for classifying crushed ores or sands, comprising a stationary inclined settling trough in which the sand settles by gravity while the slimes remain in suspension, means for conveying the sand from the trough at the upper end thereof, and means for preventing the formation of mud banks in the lower end of the settling trough comprising a lower end wall inclined at an acute angle to the bottom of the tank in front of the vertical, and side walls similarly inclined, said inclined walls being disposed in overhanging relation with respect to the portion of the conveying means arranged at the lower end of the trough.

9. An apparatus for separating and classifying materials of different settling rates, comprising a stationary inclined settling trough having a lower end wall inclined inwardly and upwardly at an acute angle to the bottom of the trough in front of the vertical and side walls inclined upwardly and inwardly at the portion thereof adjacent said end wall and adapted to prevent the formation of mud banks on either of said walls, and a launder structure about the upper edges of said inclined walls forming an overflow trough for the lower end of the settling trough, said launder being disposed outwardly of the trough with the adjacent walls of the trough forming the inner walls of the launder, said launder having its outer walls disposed in a vertical plane with the bottom edges of the settling trough.

10. An apparatus for separating and classifying materials of different settling rates, comprising a stationary inclined settling trough having a lower end wall inclined upwardly and inwardly at an acute angle to the bottom of the trough in front of the vertical, and side walls inclined upwardly and inwardly at the portion thereof adja-

cent said end wall and adapted to prevent the formation of mud banks on either of said walls, and a launder structure about the upper edges of said inclined walls forming an overflow trough for the lower end of the settling trough, said launder being disposed outwardly of the settling trough with the adjacent walls of the trough forming the inner walls of the launder, said launder having its outer walls disposed substantially in a vertical plane with the bottom edges of the trough, said launder in overhanging position to the conveying means.

11. An apparatus including conveying means

for separating and classifying material of different settling rates, comprising a stationary inclined settling trough with a lower end wall inclined upwardly and inwardly at an acute angle to the bottom of the trough in front of the vertical, and a launder structure about the upper edge of said inclined wall forming an overflow trough for the lower end of the settling trough, said launder being disposed outwardly of the settling trough and in overhanging relation to the conveying means.

5

WILLIAM EUGENE ENDREZZE.
